[57] **CLAIM**

The ornamental design for an insulative cover for undersink piping, as shown and described.

DESCRIPTION

FIG. 1 is a perspective view of a cover for an undersink pipe incorporating the new design of the invention;

FIG. 2 is a left side view thereof, the right side view is a mirror image thereof;

FIG. 3 is a rear view thereof;

FIG. 4 is a front view thereof;

FIG. 5 is a top view thereof; and,

FIG. 6 is a bottom view thereof.
